Primary Examiner — T Chase Nelson*Assistant Examiner* — Sydney Margaret Parsley(74) *Attorney, Agent, or Firm* — Goldstein Law Offices, P.C.(57) **CLAIM**

The ornamental design for a pool ladder socket cover, as shown and described.

DESCRIPTION

FIG. 1 is a perspective view of the pool ladder socket cover. FIG. 2 is a front elevational view of the pool ladder socket cover.

FIG. 3 is a rear elevational view thereof.

FIG. 4 is a top plan view thereof.

FIG. 5 is a bottom plan view thereof.

FIG. 6 is a left side elevational view thereof.

FIG. 7 is a right side elevational view thereof.

FIG. 8 is an alternate perspective view of the pool ladder socket cover; and,

FIG. 9 is a second alternate perspective view of the pool ladder socket cover.
